UNITED STATES PATENT OFFICE.

WINFIELD S. LIVENGOOD, OF KANSAS CITY, MISSOURI, ASSIGNOR TO MISSOURI HAY PRESS COMPANY, OF MOBERLY, MISSOURI, A CORPORATION OF MISSOURI.

MECHANICAL MOVEMENT.

1,108,380.

Specification of Letters Patent.

Patented Aug. 25, 1914.

Application filed November 18, 1912. Serial No. 731,994.

To all whom it may concern:

Be it known that I, WINFIELD S. LIVENGOOD, a citizen of the United States, residing at Kansas City, in the county of Jackson and State of Missouri, have invented certain new and useful Improvements in Mechanical Movements; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a mechanical movement, and more particularly to a toggle mechanism especially adapted for use in connection with the plunger head of a baling press, or like device, the principal object of the invention being to secure a compound leverage on the plunger head or driven member.

It is also an object of the invention to provide the improved details of structure hereinafter described and illustrated in the accompanying drawings, wherein:

Figure I is a perspective view of a mechanical movement constructed according to my invention, a part of the carrying frame being removed for better illustration. Fig. II is a side elevation of a part of the mechanism and the case within which it is enclosed. Fig. III is a longitudinal, vertical section of the movement as it appears when the plunger head is in its back position. Fig. IV is a view of the same parts with the plunger head advanced.

Referring more in detail to the parts: 1 designates a frame within which the movement may be mounted, the frame here shown representing the baling case of an ordinary hay press. Extending through slots 2, on opposite sides of the frame 1, so as to have both sliding and pivotal movement therein, is an axle 3, having anti-friction rollers 4 on its outer ends adapted for travel within the slotted bearings 5 which are rigidly fixed to the outer faces of the frame sides. Pivotedly mounted on the axle 3, and adapted for reciprocatory travel therewith, is a crank member 6, one arm of which has an elongated slot 8 radial with the axle 3 and through which a roller 9, journaled near the lower edges of the sides of the frame is pro-

jected to limit the reciprocatory travel of the crank and serve as a fulcrum on which the crank may turn. A second arm 10 of said crank is pivotally connected with the links 11, which are in turn pivotally mounted on a cross rod 12, carried by the plunger 13, in substantially the same horizontal plane as the axle 3. The plunger 13 may be of any suitable construction, but preferably comprises side members 14 having slots 15 through which the crank axle 3 is projected to guide the plunger during its reciprocatory travel under influence of the crank. I also prefer to provide the axle 3 with anti-friction rollers 16 over which the slotted portions of the plunger may travel, and provide the plunger with rollers 17 which are adapted to travel on the bottom of the case in order to facilitate the travel of the plunger. One end of a pitman 18 is pivotally connected with a third arm 19 of the crank 6, preferably by a pin 20 which is extended through an aperture 21 in said arm, the opposite end of the pitman being eccentrically connected with a large gear wheel 22 which is carried on a stub shaft 23 on the frame 1 and driven from a pinion 24, which may receive its power from any suitable source.

In using the movement, presuming the parts to be constructed and assembled as described, and associated with an ordinary hay press, or other mechanism with which the movement may be used, when power is applied to the pinion 24, the pitman 18 is operated to rock the crank arm 19 upwardly and thereby advance the crank arm 10. When the crank arm 10 is advanced the toggle link 11 is straightened and forward the plunger head during the forward movement of the pitman, it being apparent that when the arm 10 assumes a horizontal position the toggle link will also be horizontal, owing to the fact that the pin 12 is made to travel in substantially the same horizontal plane as the axle 3. It is apparent that, if the crank member were allowed to reciprocate freely, the plunger would be advanced only for a distance equal to the horizontal stroke of the pitman, but that by reason of the pivotal engagement of the arm 8 with the roller 9, the crank is turned as it is forwarded, so that the arm 10 and links 11 are forced to their horizontal or straightened relation, thereby lengthening the stroke

of the plunger. As the pitman returns from its forward position it exerts a pull on the crank arm 19 tending to retract the arm and at the same time pivoting the crank on its roller bearing, so that as the crank is moved backwardly the arm 10 is raised and breaks the toggle like connection between the arm 10 and link 11 until when the pitman is at its rear limit the link is in nearly a perpendicular position (Figs. I and III). It is apparent that with the mechanism described, a compound leverage or toggle movement is provided through the reciprocatory drive of the crank from the pitman and also because of the pivotal movement of the crank on its roller fulcrum. It is also apparent that the length of stroke and the leverage on the crank may be varied by changing the position of the pitman on the arm 19. It is also apparent that having the pitman eccentrically connected with the crank the links 11 are always in motion—straightening on the advancing movement and breaking on the back travel of the plunger—so that the plunger is actuated simultaneously by the reciprocatory movement and by the toggle action. It is also apparent that with the pitman and fulcrum arms of the reciprocatory crank arranged as shown, the fulcrum point of the crank recedes from its axial center as the plunger is advanced, thereby providing an increased leverage at the point where the greatest power is required.

Having thus described my invention, what I claim as new therein and desire to secure by Letters Patent is:

1. In a mechanical movement, a driven member and an axle adapted for reciprocation in the same longitudinal plane, a transmission element pivotally mounted on the axle, and provided with arms, one of which is operatively connected with the driven member, a driver operatively connected with a second arm of said element, and a fulcrum member slidably engaged by a third arm of said element.

2. In a mechanical movement, the combination with a frame having slots in its opposite sides, of an axle adapted for guided travel in said slots, a crank member carried by the axle, driving and driven members ec-

centrically connected with said crank member, and a fulcrum adapted for sliding contact by the crank member, for the purpose set forth. 55

3. In a mechanical movement, the combination with a frame having parallel slots in its opposite sides and having guide rails adjacent said slots, an axle adapted for travel in said slots and having rollers contacting the guide rails, a crank member mounted on the axle, driving and driven members having eccentric link connection with the crank member, and a stationary fulcrum adapted for sliding contact by the crank member, for the purpose set forth. 60

4. In a mechanical movement, an axle adapted for reciprocation in a fixed path, a transmission element pivotally mounted on the axle and having radial arms, one provided with a radial slot, a stationary fulcrum inclosed by the slot, and driving and driven members having pivotal connection with other of said arms. 75

5. In a mechanical movement, the combination with driving and driven members and a fulcrum, of an oscillatory and reciprocatory element having a fulcrum engaging member and having eccentric connection with both the driving and driven members whereby the driven member is actuated by either the oscillatory or the reciprocatory movement of the element independently of each other or by both simultaneously. 80

6. In a mechanical movement, a Y-shaped member having central pivotal mounting and having a slot in one of its arms, a stationary fulcrum projected through the slot and adapted for sliding contact by the arm through which it is projected, a plunger having link connection with a second arm and a revoluble driving member having pitman connection with a third arm whereby reciprocatory and oscillatory movement of the Y-shaped member is induced to reciprocate the plunger, substantially as set forth. 90

In testimony whereof I affix my signature in presence of two witnesses.

WINFIELD S. LIVENGOOD.
